UNITED STATES PATENT OFFICE.

CHARLES H. SPENCER, OF BALTIMORE, MARYLAND, ASSIGNOR TO HENRY S. DULANEY,
OF BALTIMORE, MARYLAND.

PIANO-PLAYER.

1,324,701.

Specification of Letters Patent.

Patented Dec. 9, 1919.

Application filed April 19, 1918. Serial No. 229,518.

To all whom it may concern:

Be it known that I, CHARLES H. SPENCER, a citizen of the United States of America, residing in the city of Baltimore, State of Maryland, have invented certain new and useful Improvements in Piano-Players, of which the following is a specification.

Apparatus of this type built into pianos when manufactured, the pianos being especially designed and constructed for this purpose, is well-known, such instruments being numerous and reasonably satisfactory. Other piano-playing devices designed to be sold separately and applied to pianos already in the hands of the public have been offered for sale but these are on the whole unsatisfactory because they are cumbersome and unsightly, some of them rendering the pianos unavailable for manual playing; also, they are not dependable and are expensive to install, either on account of the elaborate changes necessary to the piano action and keys or because of the fact that each of a series of player units, one for each note, must be separately mounted and connected to give considerable effort and attention to detail.

The object of the present invention is to produce an automatic piano-player action having the pneumatic units connected together or mounted on a single frame or support adapted to be inserted in the piano with the pneumatic units attached, the whole structure being so arranged that it can be applied to the piano, preferably in front of the action and above the keys and without any alteration of the piano frame or external structure, or of the piano action.

To this end, the player units are made of key width or less so that they can be arranged in a single row side by side without overlap or offset on a suitable support adapted to extend transversely of the piano and to be secured to the piano frame, each of these key width units comprising the necessary valves, a controller diaphragm and a striker or bellows, the latter having a projecting extension or lever arm adapted to connect with the corresponding unit of the piano action.

The majority of piano actions have a vertically reciprocating rod or member for each note just to the rear of the keys, which

is lifted to operate the striker and play the note and returns to normal position by gravity. This lifting is accomplished by means of the keys when the piano is manually operated. Where the present automatic playing apparatus is applied, the extension or actuating member of the bellows or striker may be brought into connection with the rod in any suitable manner by being placed beneath it or beneath any projection or beneath one of the connecting members at the top or the bottom of the rod. In the present instance, I have shown an extension member applied to a guide lever of the piano action at the bottom of the rod, the actuating members of the pneumatics being arranged to engage each such extension from beneath.

An important feature of the apparatus is that a series of player units corresponding to the notes of a piano is mounted on a single support from which any one may be separately removed instantaneously with all its parts, and replaced or repaired. The set or series and the support, which in the form of the invention shown, is the wind-pipe or chest, form a single integral structure adapted to be inserted as such in the piano, bringing the units immediately into operative relation with the corresponding units of the piano action. The pneumatic units, though in actuating relation to the piano action, are not attached and when installed can be instantaneously removed each without disturbing the others. They are also conveniently accessible for adjustment of the valves without removing.

In applying my present pneumatic apparatus to any piano made without pneumatic playing means, it is only necessary to provide some suitable means of engagement of the actuating members, if such means is not present in the action as existing, to make the transverse support for the pneumatic of the necessary length to go inside the piano casing, insert and secure it, bringing the actuating members of the pneumatics into registration with the proper points on the piano action of each note, and provide the usual music roll and tracker bar and pump in connection with the wind box which in the present instance is the support, and the installation is complete. Where other apparatus is installed under similar

circumstances, *i. e.*, in a completed instrument, such apparatus being usually beneath the keys, it is necessary to make elaborate changes, inserting each pneumatic separately and attaching it to the key, in some instances the key being itself part of the pneumatic or bellows, involving many times the expense of installation.

In the accompanying drawings I have 10 illustrated a portion of a piano to which is applied an automatic playing device, the device and the method of application being in accordance with the preferred form of my invention.

15 Figure 1 is a vertical, central, longitudinal section through the piano-player unit; Fig. 2 is an elevation of the piano action

for a single note with the piano-player unit connected;

20 Fig. 3 is a plan of the piano with portions of the case broken away to show the player units; and

Fig. 4 is a section taken transversely of the pneumatic on the line 4, 4 in Fig. 1.

25 Referring to the drawings by numerals, each pneumatic unit includes a bellows or pneumatic striker 1, a diaphragm chamber 2 with a diaphragm 3 and a valve chamber 4. The diaphragm chamber and the valve

30 chamber are formed together in a single block, split on a horizontal plane which intersects both the valve chamber and the diaphragm chamber, the upper member being indicated by reference character 5, the

35 lower member by reference character 6, and the plane of their meeting surfaces by reference character 7. The bellows or striker 1 consists of a fixed plate 8 of key width or less and of suitable length secured to the

40 bottom of the diaphragm and valve casing 5, 6, a bottom plate 9 hinged or pivoted to the top plate at the forward end at 10, and an accordion-plaited connection 11 between the plates, the same being of suitable fabric or

45 flexible material. Between the plates, I have shown a perforated spreader 12 to guide and support the fabric. Secured to the bottom plate 9 at the rear end is a suitable actuating member 14 to engage the

50 piano action and operate it to sound the note corresponding to the particular pneumatic unit. The stationary top plate 8 of the striker is apertured at 15 forming a passage to the valve chamber, and the latter has an opening 16 leading to the outside air and surrounded by a downwardly disposed valve seat 17 coöperating with

55 which is a valve 18 inside the valve chamber. Leading from the valve chamber 4 to the diaphragm chamber 2 is an opening or passage 19 surrounded by an upwardly disposed valve seat 20 coöperating with which

60 is a valve 21. The valve 18 has a stem 22 preferably provided with a screw adjust-

ment, the upper end having a key seat and 65 the lower end resting on the top of the valve 21. In the diaphragm chamber 2 is a swinging plate or lever 24 resting on the diaphragm 3 and shown as pivoted at one end remote from the valve 21 at 25. The 70 lever 24 is turned up at its swinging end at 26 against the bottom surface of the valve 21 and the latter as shown, has a depending pin 27 which enters a perforation 28 in the turned-up end 26 of the lever 24. This 75 valve 18 is also provided with guide pins 29 depending from the top wall of the valve chamber. Leading from the diaphragm chamber 2 through its top wall is an opening 30 provided with an upwardly project- 80 ing nipple 31.

The passage 15 to the valve chamber is formed in a hollow stud 151 integral with the valve chamber and diaphragm chamber structures or members 5, 6 and depending therefrom. This stud 151 is threaded externally to coöperate with a correspondingly threaded opening 152 in the fixed plate 8 of the bellows. The adjacent surfaces of the plate 8 forming part of the bellows and the 85 bottom wall of the valve and diaphragm chamber member 5, 6 are flat, so that the bellows can be rotated relatively to the said chamber members to make or break the connection which is, if desired, locked in assembled position by means of the small screw 152. The formation of this connection is such that while it is easily made tight, the parts may be immediately disassembled as 90 for application of new bellows which is the short-lived element of the structure. The convenience with which the bellows may be replaced, the units being also conveniently detached for this purpose, is an important 95 feature of the player, making its period of 100 usefulness indefinitely extensible at a comparatively small cost for repairs.

The pneumatics of the entire series are individually secured to the bottom side of the transverse wind chamber or pipe 32 110 which is rectangular in cross-section and apertured to admit the nipples 31, each of which in the preferred form has a central screw-threaded opening 33 and apertures 34 arranged around the screw socket or opening. The screw 35 is passed through the wind chamber and seated in the threaded opening 33. When tightened, it serves to draw the pneumatic unit against the wind box, securing it in assembled position. As 115 shown, the upper member 5 of the diaphragm chamber and valve chamber has a shoulder at 36 which serves to position the pneumatic unit in its relation to the wind box, the two members being preferably at 120 right angles. The diaphragm preferably has an insert 37 intermediate of its length of comparatively hard or stiff material as 125

- mica, in which is a bleeder or equalizing opening 38. The diaphragm 3, as shown, is normally horizontal or nearly so and secured at its edges between the lower surface 5 of the upper member 5 and the upper surface of the lower member 6 of the diaphragm and valve casing, by gluing or otherwise attaching to either member, preferably the lower one, to provide convenient access to 10 the lever 24 and other internal mechanism. Leading to the diaphragm chamber 2 beneath the diaphragm 3 is a tube 39 terminating outside the unit in a nipple 40 adapted to be connected each nipple to a corresponding tube 41 which in turn leads to a corresponding opening in the tracker bar not shown. The play of the bottom or swinging plate 9 of the striker is regulated and controlled by the adjustable stop screw 42.
- 15 An important feature resides in the size, external configuration and relative arrangement of the pneumatic units. The diaphragm which must be of sufficient area to control the valves, instead of being round or square, is long and narrow as shown, the length is approximately nine times the width, and this proportion has, after careful experiment, been found to be most favorable for a pneumatic which is to occupy a 20 single key space which is almost exactly one-half an inch, and the bellows or pneumatic proper is likewise elongated and made narrow, each unit being of key width or less so that the pneumatic elements can be arranged side by side in a single row without overlapping or offsetting, and the connections to the piano action all made direct and positive without cords, wires or tension members.
- 25 The pneumatic players heretofore designed having the pneumatics arranged in a single row, have been located beneath the keys, to place them in which position requires a considerable amount of special work 30 on each piano in which the player is installed. Also, the connection to the keys renders the piano unfit for manual playing until the player is removed. The applicant's pneumatic units assembled together on a 35 single support are adapted to be placed within the casing immediately adjacent the action of the piano as distinguished from the keys. Also, they are constructed to be placed in relation to the piano action so 40 that the pneumatic units merely engage the piano action units from one side, the operation of each pneumatic unit serving to thrust forward operatively a moving member of the action, permitting it to return to 45 normal position in the usual manner so that there is nothing to interfere with manual playing of the piano. The installation of the apparatus requires no change whatever in the construction of the piano or arrange- 50 ment of the action except, in the form 65 shown, the addition to each element or unit of the piano action of a shoulder, projection or extension which may be conveniently engaged by the player unit preferably during the forward, operative or working stroke 70 only so as to leave the piano action free for manual playing as already described.
- 75 In Fig. 2, there is illustrated a portion of a single unit of a piano action which may be considered typical. This action includes an upright rod 43 with suitable connections for actuating a striker when the rod is lifted. At its lower end, the rod rests on the rear end of the key lever 44 and is guided by a short guide lever 45 to which it is pivotally connected. At its upper end, the rod 43 connects with a swinging lever 46 which carries a striker actuating member. In the normal manual playing of the piano, the rod 43 is lifted when the front end of the 85 key is depressed swinging the lever 46 and actuating the striker. The same result may be accomplished by similarly lifting this rod 43 by engaging it at any other point or by engaging either the guide lever 45 or the 90 lever 46.
- 95 To apply my pneumatic playing apparatus, it is only necessary to so place the units combined as described that the actuating member 14 of each unit engages some one of the moving members of the corresponding unit of the piano action from beneath, so as to lift or actuate it each time the corresponding unit of the automatic playing apparatus is actuated. As the piano 100 action illustrated presents no such convenient point for engagement, it has been found advisable to provide a forward extension 47 of each guide lever 45 to be engaged by the actuating member of the piano action. This 105 is easily and conveniently accomplished by first slightly extending the slot 48 in the rod 43 in which the lever 45 is pivoted to admit the member 47 (it being understood that these parts are usually made of wood), 110 when, the extension members 47 having been provided in suitable size and number, one is passed through each of the extended slots 48, being laid on top of the corresponding guide lever 45 and fastened thereto by a 115 suitable screw or screws 50, or other suitable means. The guide lever 45 as shown is in the rear of the rod 43, the extension projects forwardly through the slot a suitable distance to provide convenient engagement by the actuating member of the corresponding pneumatic unit. As shown in Fig. 2, I preferably provide a striking pad 51 made adjustable relatively to the extension arm 47 by means of a screw 52.
- 120 To install the automatic player as illustrated herein, aside from the usual pumping and music roll mechanism with which

this invention has no connection, it is only necessary to apply the extension arm 47 or otherwise provide means for the engagement of the corresponding units of the piano action by the pneumatic units to lift the action as described and insert the series of pneumatics mounted on the wind chest 32 or other transverse member, securing the latter to the frame in such a position that the actuating members 14 project beneath the extensions 47 engaging the striking pads 51, or in the absence of these extensions engaging the corresponding unit of the piano action in some other convenient manner as already suggested.

As the piano action units have their corresponding points in horizontal alinement, it is important with this arrangement that the actuating members of the pneumatics should be in alinement. To this end I have devised a compact automatic playing device which can be mounted on a single support and handled as a single integral structure, as already described, by having the units of key width or less so that they can be mounted in a single row.

The arrangement herein disclosed whereby such an automatic apparatus thus assembled as an integral structure may be inserted in a convenient position where there is plenty of room for it in the casing in cooperative relation with the action, above the keys, has numerous advantages in the utilization of what may be termed used or second-hand pianos, or those otherwise already in use, for automatic playing. Some of these advantages are economy, ease and quickness of installation, practically no alteration being necessary, and maximum utility without interference with the manual playing of the piano is attained, the automatic members merely coöperating with the piano action to play each individual note and release it, in the preferred form without moving the keys. Also, there is but a single transverse support to which the player units are attached, each by a single fastening means shown in the form of the screw 35, the transverse member being in the present instance the wind box. As thus supported, any pneumatic unit can be instantly removed as an entirety for repairs or replacement by merely opening the piano casing and giving the corresponding screw 35 a few turns. Also, the valve stem 18 is exposed for convenient adjustment. The lower half of any pneumatic unit may be removed by separating the parts of the valve and diaphragm chamber on the plane 57. These features are of great importance in making it possible to keep the apparatus in condition at an extremely low cost.

I have thus described my invention specifically and in detail in order that its na-

ture and operation may be fully understood; however, the specific terms herein are used descriptively rather than in their limiting sense and the scope of the invention is defined in the claims.

I claim:

1. In combination with a piano action, an automatic playing apparatus consisting of a series of pneumatic units corresponding each to a note of the piano, placed side by side in a single row, each unit occupying no more than a single key space and having a diaphragm of almost key width and of length several times the width so placed as to lie with the long dimension substantially parallel to the keys, and transverse supporting means to which the player units are secured above the keys and in coöperative relation to the action, the support with the player units forming an integral structure adapted to be inserted or removed as a whole.

2. An automatic piano playing apparatus consisting of a series of pneumatic units of key width arranged in a single row and including one unit for each key of the piano operated by the player, supporting means to which the units are secured forming with them an integral structure, each player unit including a pneumatic air valve for controlling the admission of air to and its release from the pneumatic, and a diaphragm substantially parallel to the keys, the same being substantially of key width and of length several times its width.

3. An automatic player piano apparatus consisting of a series of pneumatic units adapted to be placed above the keyboard in coöperative relation with the piano action, the same being each of key width and arranged in a single row according to regular key spacing, each player unit including a pneumatic or bellows, means for admitting air to and releasing it from the pneumatic, and a diaphragm for actuating said means, the same being substantially parallel to the keys, of a width closely approaching key width and of a length about nine times its width.

4. An automatic piano playing apparatus comprising a series of pneumatic units of key width arranged in a single row and including one unit for each key of the piano operated by the player, supporting means to which the units are secured forming with them a single unitary structure which can be inserted and removed as a whole, each pneumatic unit with all its individual parts being separately removable from said unitary structure while said structure is in the piano, each such unit including an air valve for controlling the admission of air to and its release from the pneumatic and a diaphragm controlling said valve, the same be-

ing substantially parallel to the keys and substantially of key width and of length several times its width.

5. A pneumatic unit comprising a member including a valve chamber and a diaphragm chamber, a bellows member separately formed, a hollow stud on one member and threaded into the other member forming a passage connecting the valve chamber to the

bellows, the stud also forming means for removably securing the parts to each other.

Signed by me at Baltimore, Maryland, this 16th day of April, 1918.

CHARLES H. SPENCER.
